UNITED STATES PATENT OFFICE.

WILLIAM SMITH AND PATRICK J. SPILLANE, OF HOUSTON, PENNSYLVANIA.

TONGS.

Application filed March 22, 1922. Serial No. 545,772.

To all whom it may concern:

Be it known that we, WILLIAM SMITH and PATRICK J. SPILLANE, citizens of the United States, and residents of Houston, in the county of Washington and State of Pennsylvania, have invented certain new and useful Improvements in Tongs; and we do hereby declare the following to be a full, clear, and exact description of the invention, such as will enable others skilled in the art to which it appertains to make and use the same.

Our invention relates to tongs, and more particularly to a tong for handling sheet metal or tin-plate.

The invention consists of certain novel features and details of construction as will be more fully described hereinafter and finally pointed out in the claim.

We will now describe our invention, reference being had to the accompanying drawings, in which similar letters of reference indicate corresponding parts in the different figures, and in which Figure 1, is a plan view of the tongs, and Fig. 2, is a side elevation of the same.

A, represents one or the main section of the tong, which is provided with a jaw B, on one end thereof and with a handle-bar C, on the opposite end.

Movably secured on the section A, are auxiliary handle-bars F, and G, which are connected together by means of plates H, in such a manner as to permit the handle-bars F, and G, to slide laterally thereon. Secured to the lower ends of these bars F, and G, are links I, and J, the opposite ends of which are connected to the arm E, of the jaw D.

The plates H, are double and embrace the main section A, being rigidly riveted to the handle-bars F, and G, by means of rivets K, and are adapted to slide up and down independent of the section A.

The operation of our invention is as follows:

When it is desired to remove a bundle of sheet metal or plate from a vat, simply take hold of the handle-bar C, when the handle-bars F, and G, will drop downward, which movement in turn will cause the jaw D, to assume the open position, then grasp the bars C, F, and G, with both hands and squeeze same together which will cause the jaws B, and D, to close tight against the bundle of metal to be removed, then lift straight up and pull same from the vat.

It will be seen that by using our improved tongs, that metal may be removed from the vat much easier than by the use of the old fashioned tongs and there will be less cramping of the hands.

Having described our invention, what we claim and desire to secure by Letters Patent is:

A tong for handling sheet metal, comprising a main section provided with a jaw on one end and a handle-bar on its opposite end, auxiliary handle-bars movably secured on said section by means of plates, a jaw D, pivoted to the main section which terminates into an arm, links connected at one end to the bars F, and G, and their opposite ends to the arm of the jaw D, all substantially as and for the purposes shown and described.

In testimony that we claim the foregoing as our joint invention, we have hereunto set our hands in the presence of two subscribing witnesses.

WILLIAM SMITH,
PATRICK J. SPILLANE.
